UNITED STATES PATENT OFFICE.

LOUIS E. F. WACHTER, OF NEW YORK, N. Y.

WATCH-CRYSTAL.

1,279,617.

Specification of Letters Patent. Patented Sept. 24, 1918.

Application filed December 14, 1915. Serial No. 66,676.

To all whom it may concern:

Be it known that I, LOUIS E. F. WACHTER, a citizen of the United States, and a resident of New York city, county and State of New York, have invented certain new and useful Improvements in Watch-Crystals, of which the following is a specification, reference being had to the drawings herein referred to, which are made a part hereof.

10 This invention relates to watches and particularly to the crystal or transparent face covering. Among the objects are to produce a crystal, using the term generally, that will form a tight joint with and in the 15 casing of a watch and a secure connection, also to overcome the variations in manufacture and use of crystals and in their fitting. While I use the term "crystal," it may include any material suitable for a transparent 20 face cover of a watch or like article.

In the accompanying drawing I have shown one form of embodiment of my invention, in which A is the outer face of the crystal, B is a groove, C is a sloping or beveled portion between the groove and the main face A, D is a beveled or sloping surface between the groove and the other surface of the crystal and forms a radially extending portion of the edge. When used in 25 the form with this extending portion, the same can serve as a snap-retaining edge or a guard, or for other purposes, and would accommodate any slight irregularity of size either of the casing or of the crystal.

As such crystals are inserted in their position for use in the direction of their convexity, they are pressed and slightly bent to be snapped into position and in the case of material other than glass, as when the crystal is made of celluloid or like material which 35 is more flexible and also subject to variations, the extending edge D serves more readily to facilitate the insertion and also to guard against their falling out in the case of shrinkage. The projection C on the other 40 side of the groove prevents the crystal from falling inward.

My invention may be embodied in various forms from what I have herein specifically shown and described,—likewise the crystal 50 may be made of various material and varying dimensions, size and form, but what I claim and desire to secure by Letters Patent is:—

1. A watch-crystal having a circumferential retaining-groove formed in the center of its edge. 55

2. A watch-crystal having a circumferential groove formed in the center of its edge.

Signed at New York, this 10th day of December, 1915.

LOUIS E. F. WACHTER.
